Application March 14, 1939, Serial No. 261,807

6 Claims. (Cl. 40—34)

This invention relates to electric signs and has special reference to an electric sign designed especially for group advertising by a number of firms or by a firm with numerous places of business in one city such, for instance, as a chain-store corporation.

One important object of the present invention is to provide a novel advertising sign wherein the locations of a number of business places are successively displayed, the display of each location being accompanied by simultaneous display of advertising matter relative thereto.

A second important object of the invention is to provide a novel advertising sign representing the map of a city, display means associated therewith for indicating on said map business locations successively and other display means for displaying successive pictures of the buildings wherein the businesses are conducted.

A third important object of the invention is to provide novel circuit means for a sign of the kind described.

With the above and other objects in view, as will be presently apparent, the invention consists in general of certain novel details of construction and combinations of parts hereinafter fully described, illustrated in the accompanying drawings and particularly pointed out in the appended claims.

In the accompanying drawings like characters of reference indicate like parts in the several views, and:

Figure 1 is a front elevation of an embodiment of the invention.

Figure 2 is a side elevation thereof.

Figure 3 is a section on the line 3—3 of Figure 2.

Figure 4 is a detail elevation showing the face of a certain advertising or picture display device used herein.

Figure 5 is a detail section on the line 5—5 of Figure 2.

Figure 6 is a diagram showing the wiring of the invention.

Figure 7 is a detail section through a portion of a rotary casing used herein.

It is to be understood that this invention may be embodied in various forms and sizes. For instance, the invention may be constructed of a size suitable to be displayed in a restricted space such as a show window or may be made of sufficient size to constitute a roadside sign. Also, it is to be understood that the specific means herein shown and described for controlling the signal circuits may be varied to suit the particu-

lar construction of the invention without departing from the principles therein involved.

With this in mind, the embodiment illustrated in the accompanying drawings discloses a sign board 10 on the front face of which is delineated a plot or map 11 of a city or that portion thereof wherein the places to be advertised are located. On this map are arranged a series of small electric lamps 12 each positioned at the location of a store or other business to be advertised. On the upper part of this board 10 is preferably provided an ornamental feature such as the clock 13 although this forms no part of the invention and is not essential thereto.

Suitably secured to the board is a frame 14 carrying at its upper end portion a bearing 15 wherein is journaled the rear end of a shaft 16 having its forward end suitably supported rotatably by the board 10.

On the shaft 16 is fixed a frusto-conical casing 17 having a glazed front 18 whereon is mounted a circular series of spaced display fields showing advertisements 19 such as transparencies of the buildings wherein the several businesses defined in position by the lamps 12 are conducted. Obviously, other advertising matter may be used in place of such transparencies or the transparencies may be supplemented by such other advertising as is found desirable. This series of transparencies is concentric to the shaft 16 and in the board 10, preferably at the upper part thereof, is formed a sight opening 20 wherewith the transparencies are successively brought to registry by means to be described.

On the frame 14 is mounted a motor 21 which, through a suitable reduction gearing the casing 22 of which is shown, actuates a crank shaft 23. Fixed on the shaft 16 is a ratchet wheel 24 wherewith cooperates a pawl 25 carried by the crank shaft 23 so that rotation of the latter causes the pawl to actuate the ratchet wheel 24 with a step-by-step movement.

Mounted on the rear face of the board 10 is a circular series of evenly spaced electrical contacts 26 corresponding in number to the lamps 12. Each contact is connected by a conductor 27 to one terminal of a respective lamp 12 and the remaining terminals of these lamps are connected in multiple, as by conductors 28 to a current supply line 29. Insulatedly mounted on the casing 17 is a contact ring 30 carrying a spring contact finger 31 which engages the contacts 26 successively as the casing 17 is rotated. A spring supply contact or brush 32 constantly engages the ring 30 and is connected to a current

supply line 33. In order to illuminate the transparencies lamps 34 are mounted within the rotary casing 17 and each lamp has one terminal connected to the ring 30 by a wire 35 and its other terminal connected by a wire 36 to a contact ring 37 insulatedly mounted on the casing 17. A brush 38 constantly engages the ring 37 and is connected by a conductor 39 with the line wire 29.

10 In operation the motor actuates the crank shaft 23 which actuates the pawl 25 so that it oscillates backwardly and forwardly on the ratchet wheel 24 thereby turning the latter. This causes the casing 17 to also rotate and carries the contact 31 around to successively engage the contacts 26 and thus successively light the lamps 12. The transparencies 19 are so positioned on the casing that, as each lamp 12 is lit, the transparency corresponding to the particular lamp is brought into registry with the sight opening 29 thereby displaying matter associated with the particular location indicated by the lamp.

15 While the device is adapted for advertising purposes it may also be used to show matters of public interest and their locations. For instance, the transparencies may be in the form of views showing public buildings, statutes and the like and the lamps 12 for giving the location of the same.

20 What is claimed is:

25 1. In combination, a map board having a sight opening, display means behind said board including a series of display fields adapted to move successively into registry with said opening, lamps arranged on the map board at map locations each associated with a respective display field, a revolvable casing behind said board and having the display fields arranged on the front 30 thereof in circular series, and means to revolve said casing and simultaneously close an electric circuit through the lamp corresponding in map location to the field displayed.

35 2. In combination, a map board having a sight opening, display means behind said board including a series of display fields adapted to move successively into registry with said opening, lamps arranged on the map board at map locations each associated with a respective display field, a revolvable casing behind said board and having the display fields arranged on the front 40 thereof in circular series, means to revolve said casing and simultaneously close an electric circuit through the lamp corresponding in map location to the field displayed, said display fields being formed by transparencies, and lamps within said casing illuminating the transparencies from the rear thereof.

45 3. In combination, a map board having a sight opening, display means behind said board including a series of display fields adapted to move successively into registry with said opening,

5 lamps arranged on the map board at map locations each associated with a respective display field, a revolvable casing behind said board and having the display fields arranged on the front thereof in circular series, an electric motor, a pawl and ratchet mechanism driven by said motor and producing step-by-step rotation of the casing, and means to close electric circuits through said lamps in tuned relation to the actuation of said casing.

10 4. In combination, a map board having a sight opening, display means behind said board including a series of display fields adapted to move successively into registry with said opening, lamps arranged on the map board at map locations each associated with a respective display field, a revolvable casing behind said board and having the display fields arranged on the front thereof in circular series, an electric motor, a pawl and ratchet mechanism driven by said motor and producing step-by-step rotation of the casing, means to close electric circuits through said lamps in tuned relation to the actuation of said casing, said display fields being formed by transparencies, and lamps within said casing illuminating the transparencies from the rear thereof.

15 5. In combination, a map board having a sight opening, display means behind said board including a series of display fields adapted to move successively into registry with said opening, lamps arranged on the map board at map locations each associated with a respective display field, a revolvable casing behind said board and having the display fields arranged on the front thereof in circular series, means to rotate said casing, a circular series of contacts arranged on the back of said board and each conductively connected to a respective lamp, and a constantly energized contact carried by the casing and moving in a path to successively engage the contacts of said series.

20 6. In combination, a map board having a sight opening, display means behind said board including a series of display fields adapted to move successively into registry with said opening, lamps arranged on the map board at map locations each associated with a respective display field, a revolvable casing behind said board and having the display fields arranged on the front 25 thereof in circular series, means to rotate said casing, a circular series of contacts arranged on the back of said board and each conductively connected to a respective lamp, a constantly energized contact carried by the casing and moving in a path to successively engage the contacts of said series, said display fields being formed by transparencies, and lamps within said casing illuminating the transparencies from the rear thereof.
